UNITED STATES PATENT OFFICE.

EDWARD F. AUSTIN AND A. FRED PHELPS, OF PITTSBURGH, PENNSYLVANIA.

POWER-TRANSMITTING APPARATUS.

Application filed July 12, 1926. Serial No. 121,762.

Our invention relates to power transmission and consists in an encased unit constituting and including within itself both the reduction gear and the power-transmitting connections, by which the high-speed rotation of a prime mover is converted into the low-speed reciprocation of the stem of a pump piston or other engine part. The encased unit may be mounted integrally upon 5 and constitute one piece with the frame of the pump. The benefits of the invention include simplicity of structure, economy of space, rigidity, superior lubrication, protection of parts, cleanliness, all combined with 10 efficiency.

An embodiment of our invention is shown in the accompanying drawings. Fig. I is a view in vertical, medial, and longitudinal section of the unit in which our invention is 15 found, combined with a prime mover in the form of an electric motor and with an engine part which in this case is a pump cylinder. Fig. II is a view in vertical and transverse section, on the plane indicated at 20 II-II, Fig. I. Fig. III is a view in horizontal section, on the broken line III-III, Fig. I. Fig. IV is a vertical section, on the plane IV-IV, Fig. III.

The casing is made up of and constituted 25 by two parts 1 and 2, forming a substantially cubical box with a cover. The body of this box-like casing is constructed integrally with or mounted integrally upon the frame of the machine. In this case the 30 body of the casing is shown to be formed in a single casting with the head of the pump cylinder 3. The pump cylinder 3 extends, when the parts are assembled, horizontally. The body and the cover of the box-like 35 casing close in substantially fluid-tight engagement with one another, and upon a crank shaft 4 to which the meeting faces of the casing parts are shaped and for which these meeting faces carry bearings. When 40 the parts are assembled the crank shaft 4 extends horizontally, in common plane with the axis of cylinder 3, and perpendicularly to the axis of cylinder 3. The stem 9 of the piston within cylinder 3 extends through an orifice formed by and between the meeting 45 edges of the body and cover of the casing, and thus a guide and bearing for the piston stem are provided.

Within the casing are guides conveniently 50 in the form of rods 5 and 6 mounted one in the body the other in the cover of the casing,

and, when the parts are assembled extending horizontally, parallel one with another and aligned one above the other in vertical plane, and in parallelism with and in common vertical plane with the axis of cylinder 3. In guides such as the rods 5 and 6 afford moves a scotch yoke, consisting of the horizontally reciprocating block 7 provided with a slide-way in which a block 8 reciprocates vertically. Block 7 is rigidly connected to the stem 9 of the piston of the pump cylinder 3 and block 8 is pivotally united with the crank 10 with which the crank shaft 4 is provided. By such means manifestly shaft 65 rotation effects reciprocation of the piston within the pump cylinder.

The crank shaft carries also a worm wheel 11. Suitably journaled in the cover 2 of the casing, is a shaft 12 which when the parts 70 are assembled extends horizontally, in parallelism with guide rods 5 and 6 and with the axis of pump cylinder 3, and perpendicularly to the vertical plane in which lies the axis of crank shaft 4. The shaft 12 75 carries a worm 13 which in the assembly engages the worm wheel 11 upon the crank shaft. The shaft 12 is adapted to be driven by a prime mover, and is here shown to be coupled at 14 to, and to form a prolongation 80 of the driven shaft of an electric motor 15.

Operation is obvious. The motor, or equivalent prime mover drives shaft 12. Shaft rotation at relatively high speed is through the reduction gear shown effective 85 to drive powerfully and at low speed crank shaft 4, and rotation of crank shaft 4 effects 90 through the connection shown pump operation.

When the assembly has been completed 95 and it becomes necessary for any reason to have access to the interior of the casing, all that is necessary is to release the coupling 14. The cover 2 may then be removed from the body 1 of the casing, carrying with it and secure in position upon it the upper guide rod 6 and the shaft 12. These last named parts 100 are then freely accessible. At the same time, the removal of the cover renders freely accessible the crank shaft 4 with its worm 105 wheel, the reciprocable rod 9, and the connections between rod and shaft. Also the casing is open for the removal and renewal of lubricant.

The novel features are simplicity, compactness, enclosure in a common casing of both reduction gear and driving connections;

the mounting of the whole unitarily upon the frame of the machine, whereby alignment is fundamentally established, and permanence of adjustment and rigidity secured; closure 5 against wasting of lubrication, fowling of gears, and splashing of lubricant, and against accidental contact with oil-covered parts; the maintenance of a bath of lubricant within the casing, in which single bath 10 both the reduction gear and the driving connections find common automatic lubrication. Shafts 9 and 12 extend in parallelism and here is economy of floor space. Motor 15 may be set in axial parallelism with and 15 closely adjacent to the pump cylinder, spaced from it by only the small interval necessary for the setting of the compact casing 1, 2.

We claim as our invention:

1. In power-transmitting apparatus the 20 combination of a casing consisting of body and cover, a shaft extending within the casing and journaled between such body and cover, a reciprocable rod extending through an orifice in the casing wall formed by and 25 between the meeting edges of body and cover, the said shaft being provided within the casing with a crank and the said rod being operatively connected within said casing with such crank, and means for rotating said 30 shaft.
2. In power-transmitting apparatus the 35 combination of a casing consisting of body and cover, a shaft extending within the casing and journaled between such body and cover and provided within the casing with a crank, a pair of rods borne one by the body

of the casing and one by the cover and when the parts are assembled extending in parallelism one with another and in a common plane to which said shaft lies perpendicular- 40 and on opposite sides of said shaft, a scotch yoke borne by said rods and connected to the crank with which said shaft is equipped, and a reciprocable rod extending through the walls of said casing and en- 45 gaging said scotch yoke.

3. In power transmitting apparatus the combination of a casing consisting of a body and a cover, a crank shaft extending within the casing and journaled between the meeting edges of body and cover, a reciprocable rod extending through an orifice in the casing wall formed by and between the meeting edges of body and cover, said rod extending when the parts are assembled perpendicular to the crank shaft, two rods borne one by the body of said casing and the other by the cover and when the parts are assembled extending on opposite sides of said crank shaft and parallel one with another and with said reciprocable rod, a scotch yoke borne by and reciprocable upon said rods and operatively connected both to said crank shaft and to said reciprocable rod, a rotatable shaft journaled in the cover of said casing, and driving connection between the last-named shaft and said crank shaft and arranged within said casing. 55

In testimony whereof we have hereunto set our hands.

EDWARD F. AUSTIN.
A. FRED PHELPS.
